UNITED STATES PATENT OFFICE

MARIE K. SLEZAK, OF JAMAICA, NEW YORK

COSMETIC CONTAINER

Application filed May 18, 1931. Serial No. 538,344.

The invention relates to new and useful improvements in a cosmetic container.

An object of the invention is to provide a cosmetic container which can be made very cheaply for emergency use, and wherein provision is made for a soft coherent cosmetic, as well as for puffs impregnated with a powder cosmetic.

A further object of the invention is to provide a cosmetic container of the above type wherein the soft coherent cosmetic is covered and shielded, and wherein the puffs impregnated with powder cosmetic are rendered easily accessible.

15 In the drawing which shows by way of illustration one embodiment of the invention—

Figure 1 is a front view of a cosmetic container with the cover raised, showing the 20 inner structure and contents of the container;

Fig. 2 is a vertical sectional view through the container shown in Fig. 1;

Fig. 3 is a face view of a portion of the 25 wrapper of the container and showing the receptacle for the soft coherent cosmetic;

Fig. 4 is a sectional view on the line 4—4 of Fig. 3, and

Fig. 5 is a plan view of one of the puffs 30 which is impregnated with powder cosmetic.

The invention consists of a cosmetic container which includes a wrapper which is preferably made of paper. Attached to the 35 wrapper are three partitions, likewise preferably of paper. The lower part of the wrapper is folded about the lower ends of the partitions, and a securing means is passed through the wrapper and partitions 40 for holding said parts in fixed relation to each other. Attached to the inner face of the wrapper directly in rear of and opposite the rear partition is a member preferably annular in shape, and forming a receptacle for the soft coherent cosmetic. Fibrous powder puffs, preferably disk-shaped, and impregnated with a powder cosmetic, are adapted to be placed in the pockets formed between the partitions.

50 The partitions are of different heights so

that these powder puffs, when two or more are used, may be rendered readily accessible. The wrapper folds down over the partitions and the lower end thereof may be tucked underneath the folded back portion of the 55 wrapper for holding the same in place, thus forming a compact container.

Referring more in detail to the drawing, the invention as illustrated is embodied in a container which consists of a wrapper 1. 60 This wrapper is preferably made of paper. Associated with the wrapper are a series of partitions. As illustrated, there are three partitions, a rear partition 2, a front partition 3, and an intermediate partition 4. 65 The wrapper 1 is folded back as indicated at 5, and thus encloses the lower ends of the three partitions. A securing means, preferably in the form of a staple 6, is passed through the wrapper, firmly clamping the 70 folded back portion of the wrapper and the partitions against the rear portion of the wrapper. These partitions, as clearly shown in the drawing, are of different heights. The front partition is the lowest and the rear 75 partition is the highest. Attached to the inner face of the wrapper is an annular member 7 preferably of pasteboard, which has some considerable thickness, and this forms a receptacle 8 in which a soft coherent cosmetic 80 may be placed. The cosmetic placed in this receptacle is of the character usually referred to as a lip stick cosmetic. Between the partitions 2 and 4 is a pocket in which is placed a powder puff 9 made of any suitable felted or fibrous material, and this powder puff is shown disk-shaped. The powder puff is impregnated with a powder cosmetic. Between the partitions 3 and 4 is a pocket 85 adapted to receive a similar powder puff 10 which is likewise impregnated with a powder cosmetic. Any number of partitions may be provided, and any number of powder puffs may be stored in the pockets thus formed, so that powder puffs having different 90 colored cosmetics may be stored within the container.

The staple 6 is passed through a wrapper at a short distance beneath the edge 11 of the folded back portion 5. The upper por-

tion of the wrapper may be readily folded to the broken line position shown in Fig. 2, and the end thereof inserted between the upper edge portion 11 and the partition 3. 5 When forced in between these parts, it will be firmly clamped.

From the above it will be apparent that I have provided a container for cosmetics which may be cheaply made, and is, therefore, particularly advantageous as an emergency cosmetic compact. These small containers may be readily stored and delivered from vending machine, as well as sold over the counter.

15 It is obvious that minor changes in the details of construction and the shaping of the parts may be made without departing from the spirit of the invention as set forth in the appended claims.

20 Having thus described the invention, what I claim as new and desire to secure by Letters-Patent is,—

1. A container for cosmetics comprising a wrapper having partitions providing separate pockets, an apertured member secured to the inner face of the wrapper opposite a partition and providing a receptacle for a soft coherent cosmetic, said pockets being adapted to receive removable puffs impregnated with a powder cosmetic.

2. A container for cosmetics comprising a wrapper having partitions providing separate pockets, an apertured member secured to the inner face of the wrapper opposite a partition and providing a receptacle for a soft coherent cosmetic, said pockets being adapted to receive removable puffs impregnated with a powder cosmetic, said wrapper and partition being formed of paper, and the wrapper being folded about the lower edge portions of the partition and secured by stapling, the upper portion of said wrapper being foldable over the partition and puffs for covering the same.

45 3. A container for cosmetics comprising a wrapper having partitions providing separate pockets, an apertured member secured to the inner face of the wrapper opposite a partition and providing a receptacle for a soft coherent cosmetic, said pockets being adapted to receive removable puffs impregnated with a powder cosmetic, said wrapper and partition being formed of paper, and the wrapper being folded about the lower 50 edge portions of the partition and secured by stapling, the upper portion of said wrapper being foldable over the partition, and puffs for covering the same, said partitions being of different heights so as to expose and 55 render accessible the powder puff placed in the pocket between the partitions.

4. A container for cosmetics comprising a wrapper, flexible partitions rigidly connected to said wrapper and forming therebetween pockets adapted to receive removable

puffs impregnated with a powder cosmetic, said wrapper having a flap for covering the partitions and closing the pockets, and a receptacle within the wrapper for a soft coherent cosmetic.

In testimony whereof, I affix my signature.
MARIE K. SLEZAK.
